(57) **CLAIM**

The ornamental design for a hair curler, as shown and described.

DESCRIPTION

FIG. 1 is a first perspective view of a hair curler showing our new design.

FIG. 2 is a front view thereof.

FIG. 3 is a back view thereof.

FIG. 4 is a left side view thereof.

FIG. 5 is a right side view thereof.

FIG. 6 is a top view thereof.

FIG. 7 is a bottom view thereof.

FIG. 8 is a front elevation view thereof, shown in a position of use; and,

FIG. 9 is a front elevation view thereof, shown in a second position of use.

The broken lines illustrate portions of the hair curler and form no part of the claimed design.
